GIOVANNI B. OTTAVIANO, OF NEW YORK, N. Y., ASSIGNOR TO AMERICAN PIANO
AND ACTION COMPANY, A CORPORATION OF WEST VIRGINIA.

COMBINED TRACKING, TRANSPOSING, AND SUSTAINING MECHANISM.

1,293,179.

Specification of Letters Patent. Patented Feb. 4, 1919.

Application filed July 20, 1915. Serial No. 40,878.

To all whom it may concern:

Be it known that I, GIOVANNI B. OTTAVIANO, a subject of the King of Italy, residing in the city, county, and State of New York, have invented certain new and useful Improvements in Combined Tracking, Transposing, and Sustaining Mechanism, of which the following is a specification.

In piano players an opening for sustaining desired notes or otherwise controlling the accent to be given to such notes is sometimes provided in the tracker bar just beyond the end (usually the left end) of the note openings and the note sheets are provided with perforations adapted to register with this accent-controlling opening. When the perforations in the sheet are passing over the accent-controlling opening air is admitted therethrough and this admission of air causes the operation of pneumatic mechanism of a known type to operate the usual damper or other accenting means. When the series of perforations in the sheet terminate the margin of the sheet closes the accent-controlling opening in the tracker bar and the accent means returns to its ordinary position. The present invention provides a mechanism whereby a combination of effects is achieved. First, the note sheet is caused to track correctly, that is to travel with its note perforations registering accurately with the note openings in the tracker bar. Second, a transposing device is provided by which the sheet may be caused to travel in a line to the right or to the left of what we may call the normal position, so that its perforations will register with note openings in the tracker to the right or to the left of those with which they were intended to register and thus will play the music in a higher or in a lower key. And third, an accent controlling device is provided; and the parts are so designed and arranged that for a variety of keys the apparatus will continue to track perfectly and to accent the notes as desired, the relations between the several mechanisms being adjustable so that for all keys within the range of the apparatus they will continue to function perfectly. Furthermore, the mechanism is so designed as to cover a comparatively large range of transposition to different keys without interfering with the tracking and accent-controlling operations.

The accompanying drawings illustrate 55 apparatus embodying the invention.

Figure 1 is a front elevation showing a music sheet passing over the tracker bar with the parts in normal position, that is so as to play the music in the key for which 60 the sheet has been perforated;

Figs. 2 and 3 are similar views showing the parts adjusted so as to play the music in a key one note higher than the normal and two notes higher than the normal re- 65 spectively;

Fig. 4 is a similar view showing the parts adjusted to play in the normal key, with dotted line indications of adjustments to lower keys;

Figs. 5, 6 and 7 are similar views showing the parts adjusted for one, two and three notes below the normal respectively;

Fig. 8 is a rear elevation of the principal parts of Fig. 1;

Fig. 9 is a section through the right hand end of the tracker bar parallel to the face thereof;

Fig. 10 is a front elevation of another style of mechanism which is similar in construction but has not the range of adjustment of the mechanism shown in Fig. 1;

Fig. 11 is a rear elevation of the tracker bar of Fig. 10;

Fig. 12 is a longitudinal section of the 85 right hand end of this tracker bar, on a plane parallel with the face thereof.

Referring to the embodiment of the invention illustrated, the tracking mechanism operates on the principle described in the Turney application for Patent No. 695,511, filed May 6th, 1912, no claims being made herein to the tracking mechanism except in combination with other features of the present apparatus.

The tracker bar comprises a note member A having openings as in the ordinary simple tracker bar for causing the striking of notes as they register with the perforations in the note sheet, a tracking-control portion B and an accent-controlling portion C. During the playing of a piece of music these portions of the tracker bar remain in a determined position relative to each other and are all automatically adjusted slightly to the right or to the left as the sheet runs out of line to the right or to the left so as to preserve the correct registration of the note

- perforations in the sheet with the note openings of the portion A of the tracker bar. The tracking mechanism in the construction illustrated effects an automatic movement 5 of the tracker bar to accommodate lateral variations of the sheet; but there are numerous mechanisms known for securing the same result by shifting the sheet to the right or to the left as the occasion requires, and 10 there are other known mechanisms for shifting the tracker bar. While I prefer to use the tracking mechanism illustrated it may be substituted by any other usual or suitable mechanism for accomplishing this purpose. 15 The tracking-control portion B of the tracker has a small opening D communicating by a tube E with a tracking-control bellows or pneumatic comprising a fixed board or plate F and a movable board or plate G. 20 This pneumatic communicates through a bleed opening H with a tube J which runs directly to the wind chest or vacuum in which there is always a suction during the playing of a piece of music. The tracking- 25 control portion B of the tracker is fastened to a rod K which runs along the back of the tracker bar and has on its opposite end an adjustable end piece L which bears against an arm M projecting laterally and 30 forwardly from the movable board of the bellows, to which it is attached. The end piece L provides an adjustable shoulder on the rod K and a spring N is arranged between this shoulder and the left hand member 35 O of the spool box or frame in which these parts are mounted. The right hand member of the spool box is indicated at P and it will be understood that the music roll and the winding-on roll are carried in 40 the spool box above and below the tracker bar respectively so that the sheet Q is fed downward from the music roll on to the winding-on roll and passes closely over the face of the tracker bar. 45 During the playing of a piece of music the right hand edge of the note sheet partially overlaps the tracking-control opening D, leaving a small portion thereof uncovered. Air is, therefore, admitted through 50 the opening D into the bellows F, G, and at the same time is sucked out of the bellows through the bleed opening H. In the normal running of the sheet the covered area of the opening D is just equal 55 to the area of the bleed opening H. If the sheet shifts to the right, reducing the uncovered area of the guide-opening D, the suction in the bellows will increase and the latter will be collapsed sufficiently to press 60 the rod N and the portion B of the tracker bar to the right so as to uncover a greater portion of the guide-opening and thus hold the tracker bar in correct position relative to the sheet. If the sheet shifts to the left 65 air will be admitted through the opening D

into the bellows faster than it is being exhausted therefrom, the suction therein will be reduced and the spring N will shift the rod K to the left and with it the portion B of the tracker bar, and so on. The left 70 hand end of the tracker bar passes through the side O of the spool box. The right hand end is provided with pins R passing through the side of the spool box; the tracker being adapted to slide thus to the 75 right or to the left under the influence of the pneumatic and the spring N.

The note-member A of the tracker bar is arranged for adjustment to the right or to the left relative to the tracking-control portion B. For this purpose it carries a rod S sliding through a sleeve in the portion B and another rod T which also passes through a sleeve in the portion B but is screw-threaded and surrounded by a nut U 80 fixed against longitudinal movement in the portion B and exposed at the front of the machine. The operator, therefore, by turning the nut B up or down with his finger can shift the note-member A to the right 85 or to the left relatively to the tracking-control portion B. Assuming the line of travel of the note sheet to be fixed, as is practically the case, and the portion B of the tracker to be 90 fixed because of the relation of the guide-opening D to the edge of the sheet, the turning of the nut U may be made to shift the note member A of the tracker a distance of any desired number 95 of note-openings to the right or to the left so as to bring the note-openings which are lower or higher in the scale into register with determined note perforations in the sheet and thus cause the playing of the 100 music in a lower or a higher key, as desired. A scale V is marked on the portion B of the tracker bar and a pointer W is fixed to the portion A and indicates the distance to which the latter is to be adjusted 105 to the right or to the left to raise or lower the key by one or more notes.

The accent-controlling portion C of the tracker bar has an opening X which communicates at the back with a tube leading to the damper-lifting mechanism as usual or to any usual or suitable accent-controlling mechanism. On the face of the tracker bar the opening is made of such a width that it will underlie the line of the accent controlling perforations Y in the sheet in any 115 one of three different lateral positions corresponding to three different keys for the music. Fig. 1 indicates one such position in full lines and two others in dotted lines. Fig. 2 indicates the position when the part 120 A of the tracker is shifted one step to the left to raise the key of the music one note and Fig. 3 indicates the position for a raise of two notes. The length of each step through which the parts are shifted is sub- 125 130

stantially equal to the distance between centers of adjacent note openings in the tracker bar. There is a limit to the length which may be given the opening X and the range 5 of transposition in machines having such an accent-controlling opening where the parts A and C move together as in Figs. 1, 2 and 3, this range being dependent on the width of the margin of the paper from the 10 lowest note perforation Z to the edge of the sheet. The accent-controlling perforations Y should be in about the middle of the margin so that in one extreme position (Fig. 1) the lowest note perforation will clear the 15 right hand end of the opening X so as to avoid unintentional operation of the accenting device and in the opposite extreme position (Fig. 3) the edge of the sheet will clear the left hand end of the opening X: 20 and consequently the length of the opening X cannot be greater than about one-half the width of the margin of the sheet. This with sheets of the present standard allows for playing the music in three keys.

25 In the mechanism of Figs. 1 to 9, however, means are provided by which this limit is doubled. A change of key is permitted by moving the note-controlling portion A of the tracker bar relatively to the accent-controlling portion C. This movement alone 30 may be provided, the portion C being fixed, and will permit transposition through a greater range. The range of adjustment in fact is limited only by the total width of 35 the sheet and the consequent distance between the part B and the guide-opening D at one side and the part C and the opening X at the other side; and X, being fixed and not necessarily larger than the perforations 40 Y, might be near the edge of the sheet, the line of the perforations Y being correspondingly located.

But in using note sheets now on the market, with accent-controlling perforations Y in 45 about the middle of the margin, the greatest range of transposition is secured by combining the two systems above described; making the portion C of the tracker bar movable with the note portion A when the 50 latter is shifted in one direction from a determined position and holding the portion C stationary when the portion A is moved in the opposite direction from said position. The starting position is shown on the 55 scale V by a heavy line α . When the pointer W is shifted to the left of this starting line the key is raised and it may be raised one or two notes. When the pointer is shifted to the right of the line α the key is lowered one, 60 two or three notes. Thus a range of six notes is secured.

To secure this result the accent controlling portion C is made to follow the note portion A in its movements to the left from 65 the starting position. Fig. 1, as explained;

but during a movement of the note portion A to the right of the starting position the sustaining portion C is unmoved. This operation is secured by arranging a sliding connection between the parts A and C, by 70 means of the rod K and a rod b both fixed to the part A and sliding through tubular portions of the part C, by locating a spring d on the rod b pressing at one end against a collar e on said rod and at the opposite end 75 against a shoulder on the part C, and by providing a stop pin f on the part C adapted to bear against the outer face of the fixed side member O of the spool box. A stop pin g is also provided on the part C adapted to 80 strike the inner face of the side member O to prevent over adjustment to the left which would bring the opening X beyond the edge of the note sheet.

Fig. 4 shows in full lines the parts at the 85 starting point and in dotted lines the successive positions of adjustment for lower keys, and Figs. 5, 6 and 7 show respectively the positions for keys one, two and three 90 notes lower than the starting point. Further adjustment in this direction is prevented by the end of the note portion A of the tracker bar striking the tracking portion B.

Figs. 10, 11 and 12 show a construction in 95 which the note portion A and the accent-controlling portion C are not separately movable. In this case the range of adjustment is only three notes, that is one note above or one note below an assumed starting point. An indicating scale is shown in Fig. 10 marked on the portion C of the tracker bar and utilizing the left hand edge of the paper as a pointer; the starting line α' of the scale being covered and the extreme 100 left hand line being in register with the edge of the sheet. As the note portion of the tracker bar is shifted to the left from this position the central line α' of the scale will first be exposed and then the right hand 110 line. In other respects the construction is the same as that of Figs. 1 to 9, omitting only the yielding connection between the parts A and C; the details being shown in Figs. 11 and 12.

In many machines there is no automatic 115 correcting of lateral deviations in the line of travel of the sheet, dependence being had upon accurate workmanship alone to insure straight running of the sheet. In using my 120 invention in such machines the pneumatic correcting mechanism shown at the left of Fig. 1 would be dispensed with, and the member B would be fixed and would be a tracking member in the sense of determining 125 an accurate registration of the note perforations in the sheet with desired note openings in the member A, but would not correct accidental lateral deviations of the sheet 130 from the true line of travel.

In the previous Turney application for an automatic tracking device above referred to, as well as in Turney Patent No. 1,056,858 of March 25, 1913, for a similar automatic tracking device, the adjustable tracking member shown was used only to adjust the relation of the tracker to the sheet for such slight differences as are found between different note sheets or as are found at different times and under different atmospheric conditions in the same note sheet, and the device was not designed nor adapted for such an extent of adjustment as to transpose the key of the music. I believe it is new with me to combine means for automatically tracking, or correcting accidental lateral deviations, with means for shifting the relative lateral position of the note openings in the tracker by distances equal to one or more notes so as to transpose the key; and to provide a scale by which the extent of the transposition could be measured.

Though I have referred to the parts B and C as portions of the tracker bar yet it is chiefly for simplicity of construction that they are arranged as continuations of the note portion A. They may be arranged at other points in the line of travel of the sheet and either of them may be located at either side, or they may both be arranged on the same side. Though I have assumed a fixed line of travel for the note sheet and have explained the operation on that assumption, yet it will be understood that only relative lateral movement between the perforations in the sheet and the openings of the tracker bar is required in order to transpose the key, and this may be secured by shifting the note portion of the tracker bar as described or by reversing the parts and shifting the sheet as in many known automatic tracking mechanisms. And though I have described with great particularity of detail certain specific embodiments of my invention, yet various other modifications may be made by those skilled in the art and various parts thereof may be utilized in other combinations than those described without departing from the invention.

50. What I claim is—

1. A player for pianos or the like including in combination a note member having openings for causing the striking of the notes as perforations in a note sheet register with such openings, an accent controlling member having an opening for controlling the accent of the notes as perforations in the sheet register with said opening, means for effecting a relative adjustment laterally between the sheet and said note member and accent-controlling member, said accent-controlling opening being large enough to register with the corresponding perforations in the sheet in a plurality of such relative lateral positions.

2. A player for pianos or the like including in combination a note member having openings for causing the striking of the notes as perforations in a note sheet register with such openings, an accent controlling member having an opening for controlling the accent of the notes as perforations in the sheet register with said opening, means for effecting a relative adjustment laterally between the sheet and said note member and accent-controlling member, said accent - controlling opening being large enough to register with the corresponding perforations in the sheet in a plurality of such relative lateral positions, and means for automatically correcting accidental lateral deviations of the sheet relative to said note openings.

3. A player for pianos or the like including in combination a note member having openings for causing the striking of the notes as perforations in a note sheet register with such openings, an accent controlling member having an opening for controlling the accent of the notes as perforations in the sheet register with said opening, means for effecting a relative adjustment laterally between the sheet and said note member and accent-controlling member in one direction, said accent-controlling opening being large enough to register with the corresponding perforations in the sheet in a plurality of such relative lateral positions, and means for effecting a relative adjustment laterally between the sheet and said note member alone in the opposite direction.

4. A player for pianos or the like including in combination a note member having openings for causing the striking of the notes as perforations in a note sheet register with such openings, an accent-controlling member having an opening for controlling the accent of the notes as perforations in the sheet register with said opening, means for effecting a relative adjustment laterally between the sheet and said note member and accent-controlling member in one direction, said accent-controlling opening being large enough to register with the corresponding perforations in the sheet in a plurality of such relative lateral positions, means for effecting a relative adjustment laterally between the sheet and said note member alone in the opposite direction and means for automatically correcting accidental lateral deviations of the sheet relative to said note openings.

5. A player for pianos or the like having a tracker bar comprising the following members, namely, a note portion having openings for causing the striking of the notes as they register with perforations in a note sheet and an accent-controlling portion having an opening for controlling the accent of the notes as it registers with per-

forations in the sheet, in combination with means for effecting a relative adjustment laterally between the sheet on the one hand and said note portion and accent-controlling portion together on the other hand to transpose the key of the music.

6. A player for pianos or the like having a tracker bar comprising the following members, namely, a note portion having 10 openings for causing the striking of the notes as they register with perforations in a note sheet and an accent-controlling portion having an opening for controlling the accent of the notes as it registers with perforations in the sheet, in combination with means for effecting a relative adjustment laterally between the sheet and said note portion and accent-controlling portion together to transpose the key of the music in 15 one direction and means for effecting a similar adjustment of the note portion alone in the opposite direction.

7. A player for pianos or the like having a tracker bar comprising the following members, namely, a note portion having openings for causing the striking of the notes as they register with perforations in a note sheet, a tracking portion carrying means for effecting a relative adjustment laterally 20 between the sheet and said note portion to transpose the key of the music and an accent-controlling portion having an opening for controlling the accent of the notes as it registers with perforations in the sheet, in 25 combination with means controlled through said tracking portion of the tracker bar for automatically correcting lateral deviations of the sheet relative to said note openings.

40 8. A player for pianos or the like having a tracker bar comprising the following members, namely, a note portion A, a tracking portion B, and an accent-controlling portion C, said note portion A being adjustable laterally toward and from said tracking por-

tion B, a spring pressing said portion C against said portion A so that the two move together through a portion of the range of such adjustment, and a stop for holding the portion C against movement with the portion A during the remaining portion of such range.

9. A player for pianos or the like having a tracker bar comprising the following members, namely, a note portion A, a tracking portion B, and an accent-controlling portion C, said note portion A being adjustable laterally toward and from said tracking portion B, a spring pressing said portion C against said portion A so that the two move together through a portion of the range of such adjustment, and a stop for holding the portion C against movement with the portion A during the remaining portion of such range, and pneumatic mechanism controlled 60 in accordance with the lateral relation of said sheet to said tracking member for correcting lateral deviations of the sheet from its intended line of travel.

10. In a combination, a tracker-bar, note-sheet feeding rollers, means for automatically shifting the tracker bar relatively to the note-sheet rollers to aline the perforations in the note-sheet with the openings in the tracker-bar, a block at one end of the 70 tracker-bar provided with a guide-opening covered and uncovered by the edge portion of the note-sheet for controlling the operation of the automatic shifting means, and manually operated means for adjusting the 75 block to different positions spaced apart from each other equal to the distance separating openings in the tracker-bar, whereby the tracker-bar and note-sheet are automatically shifted relatively to each other 80 to an extent sufficient to produce transposition into different keys.

In witness whereof I have hereunto signed my name.

GIOVANNI B. OTTAVIANO.
